(57) CLAIM

The design for a power saw, as shown and described.

DESCRIPTION

FIG. 1 is a front view of the power saw;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a perspective view thereof.

The broken lines shown in the drawings represent portions of the power saw that form no part of the claimed design.
